PORTABLE SCAFFOLDS

Clyde W. Frosser, 217 Oriole Drive, Pittsburgh, Pa.
Filed Oct. 15, 1962, Ser. No. 230,595
4 Claims. (Cl. 182—142)

The present invention relates to portable scaffolds and particularly to a portable scaffold structure and elevator device for carrying material to the scaffold as the scaffold is moved within the work. The invention is particularly directed to scaffolds for use in vessels having an opening smaller than the interior diameter such as is found in the Kaldo furnace, L.D. vessels, Bessemer converters, blast furnaces and the like. These furnaces vary in diameter from top to bottom. The Kaldo furnace is typical of such structures. In the Kaldo furnace the opening is smaller than the diameter of the furnace intermediate the two ends and at the bottom is again reduced in a truncated cone-like form. Usually the bottom is removable so that access into the interior of the furnace may be had either from the top opening or from the bottom. The lining of these furnaces creates a very real problem in scaffold structure because of the need for a cantilever construction at the mid-area of the vessel. In the past, this has required continuous scaffolding; first, for the purpose of removing the old lining and then to place the new lining. This required that the scaffold be built and then torn down piece by piece as the old lining was removed and, thereafter, rebuilt piece by piece until the new lining was installed, and then finally torn down piece by piece for final removal. Since these furnaces must be relined frequently, usually after a week's run, this scaffolding problem has become quite expensive and serious. In addition, there is the associated problem of delivering supplies to the workmen and removing debris. This has in the past been done by conventional crane hooks lowering a container through the opening of the furnace down to the scaffold level. The workmen had to be removed in order to safely operate the crane or take the risk of serious injury if any slip occurred in the rigging carrying the materials and supplies.

I have invented a scaffold and elevator structure which overcomes the problems mentioned above and which is simple, inexpensive and readily portable. Preferably I provide a plurality of hollow, elongated scaffold members telescoping within one another, cooperating lock means on the top and bottom of each said member adapted to hold the bottom of one member adjacent the top of the next smaller member in extensible position, support arms hinged at the top of the largest member adapted to be raised to the horizontal position and held there, removable grating means on said arms, means on the said largest member adapted to receive a crane hook whereby said member may be raised in the furnace, a plurality of spaced guides made up of telescoping guide members adapted to rest within one another, one of said guide members of each guide being attached to the largest scaffold member radially spaced from the center thereof and extending transversely from the plane of the top end thereof to form an adjustable elevator shaft, cage means movable within said telescoping guide members and resiliently mounted guide wheels or rolls on said cage bearing on said telescoping guide members holding said cage centered therebetween. The spaced guides may be extended vertically upwardly from the top surface of the largest member or they may extend vertically downwardly through the opening in the bottom of a furnace. Preferably a loading platform is provided at the opposite extreme of the guides from the

2

scaffold at which point the cage may be loaded with supplies. The scaffold members may take the form illustrated in my copending application Serial No. 99,255 filed March 29, 1961, now Patent No. 3,058,543.

- 5 In the foregoing general description I have set out certain of the objects, advantages and purposes of my invention. Other objects, purposes and advantages will be apparent from a consideration of the following description and the accompanying drawings in which,
- 10 FIGURE 1 is a vertical section through a furnace and scaffold and elevator unit according to my invention with the scaffold in its lowest position;
- 15 FIGURE 2 is a section on the same line as that of FIGURE 1 but with the scaffold extended and the elevator guide removed;
- 20 FIGURE 3 is a vertical section through a furnace showing a second embodiment of my invention;
- 25 FIGURE 4 is a section on the same line as FIGURE 3 showing the scaffold partially extended;
- 30 FIGURE 5 is a section on the same line as FIGURE 3 showing the scaffold fully extended; and
- 35 FIGURE 6 is a section through a furnace showing a third embodiment of my invention;
- 40 FIGURE 7 is a fragmentary section through a portion of the plurality of cylinders showing the removable locking pins;
- 45 FIGURE 8 is a fragmentary view of the side of the elevator cage and guide showing the resilient wheels;
- 50 FIGURE 9 is an enlarged vertical section of the elevator guide tubes and scaffold showing the screen assembly.
- 55 Referring to the drawings, I have illustrated a furnace 10 of the Kaldo type having a truncated top terminating in a reduced opening 11 and a truncated bottom 13 having a reduced opening 12 with a removable bottom 13. The furnace is lined with brickwork 14. A scaffold base 15 is adapted to rest on the removable bottom 13 or, alternatively, on an adjustable support later to be described. A plurality of cylinders 16, 17, 18, 19 and 20 are held together by a series of removable pins 16a, 17a, 18a and 19a which pass through openings in the sidewalls of the cylinder as described in my copending application Serial No. 99,255 and telescoped one about the other so as to rest on the base 15. The largest cylinder 20 is provided with a lift bar such as is disclosed in my copending application. The lift bar is adapted to receive a crane hook whereby the unit may be inserted in the furnace through the opening 11 and may be extended in the furnace. Each of the cylinders 16 through 20 are provided at the top and bottom with cooperating openings at the top and at the bottom through which lock pins may be inserted, all as described in my copending application. The top of the outer cylinder 20 is provided with hinged arms 21 adapted to fold against the sides of the cylinders. These arms when extended are adapted to receive removable grating sections 22 which form a work surface. A plurality of guides made up of telescoping units 23, 24, 25, 26, 27, 28 and 29 are spaced radially from the center of the scaffold members and are fixed at one end by attaching member 30 to the top V section 20 of the scaffold. At the opposite end these guides are fixed to a charging platform 31. Preferably the members are graduated from large diameter at each end to a smallest diameter in the middle of the guide. A cage 32 is adapted to slide between these guides on guide wheels or rolls 33 which are mounted on lever arms 33a pivoted to the side of the cage by a pivot pin 33b and urged toward the guide by a spring 33c as the cage is lifted. The cage is provided with a lift bar 34 adapted to receive a lift hook 35 on a cable 36 which may be from an overhead crane or from a similar source of lifting power.

Screens 23a are fixed to each two adjacent top guide members 23. Telescoping screens are slidable dependent from screens 23a and terminate in bottom screens 29a fixed to the bottom guide member. The intermediate screens 24a, 25a, 26a, 27a and 28a may or may not be fixed to their corresponding guide members but only to guideways in the adjacent screens. These screens telescope with the guide members forming a completely protected shaft.

When it is desired to use the scaffold the scaffold is lowered through the opening 11 by a crane hook until the base 15 rests on the bottom of the furnace. The arms 21 are raised to their extended position and the removable gratings 22 applied. The bottom tube 29 of the guide members or tubes is fixed by the attaching member 30 to the scaffold. The upper member 23 of the guide members is fixed to the platform 31. The cage 32 is inserted between the guides with the guide rolls bearing against the guide members. The cage is raised and lowered to carry supplies to the platform by means of the cable 36 and hook 35. When it is necessary to raise the scaffold the hook 35 is lowered past the cage 32 to engage the lift bar on the upper scaffold member 20. The pins between two of the scaffold members which have not been extended are removed. The cable 36 is raised separating the two members from which the pins have been removed until the bottom of the larger approaches the top of the smaller. The pins are then reinserted, all as described in my copending application Serial No. 99,255. While the upper member 20 is being raised the guide members forming the elevator shaft are being compressed along with their corresponding screens and the lowermost member 29 and the corresponding screen 29a telescopes into the next adjacent member 28 and 28a respectively. This same operation is repeated each time that it is necessary to raise the work platform.

In FIGURES 3, 4 and 5 I have illustrated a second embodiment of my invention in which like elements are identified with like numbers with the addition of the letter "a." In the figures, I have illustrated a Kaldo furnace with the removable bottom taken away. In the embodiment here illustrated I have shown a scaffold having a base 40 adapted to rest on a portable scaffold support 41'. The base 40 and the top of the scaffold support 41' are provided with an opening 42' through which access may be had to the interior of the scaffold. The scaffold is made up of a plurality of cylinders 41, 42, 43, 44, nesting one within the other as in the case of FIGURE 1. The largest of these scaffold members identified by the number 44 is provided with a lifting yoke 45 fixed to the periphery thereof. This lifting yoke carries a lifting rod 46 on link arms 47 swiveling on pins 48 in the top of yoke 45. The lifting bar 46 is adapted to be engaged by a crane hook 49 on a cable 50. The largest of the scaffold members 44 is also provided with hinged arms 51 adapted to fold against the side of the cylinder as illustrated in FIGURE 3. These arms 51 are adapted to be extended and to receive a plurality of removable gratings 52 which serve as a working surface. An elevator cage 53 is adapted to be moved centrally through the opening 42 in the scaffold base 40 axially of the scaffold members through an opening 54 in the top of the several scaffold members. The cage 53 is provided with a lift bar 55 which is adapted to be engaged by the crane hook 49 to lift supplies from a loading station within the scaffold support 41 to the level of the work platform 52. The scaffold members are pinned together and raised and lowered as described in my copending application Serial No. 99,255.

In the embodiment illustrated in FIGURE 6, I have illustrated an apparatus identical with that of FIGURES 4 and 5 but provided with a telescoping elevator shaft and cage. In this embodiment, parts which are identical with those of FIGURES 4 and 5 bear like numbers with the suffix "b." The furnace and scaffold are identical with

those of FIGURES 4 and 5 and no further description of them is deemed necessary.

Telescoping guide members 60, 61, 62, 63, 64 and 65 are spaced radially around the axis of the scaffold 5 within the scaffold at the corners of opening 42'b. The upper member 65 is fixed to the top scaffold member and the lower member 60 is fixed to the base of the scaffold support 41b. A cage 66 moves within the guide members 67 bearing on the guide members to hold the cage 66 within them. The cage 66 is provided with a lift bar 68 adapted to receive the lifting hook 69 of a lift cable 70 from a suitable power source.

Supplies are loaded on cage 66 within the scaffold support 41'b and raised to the level of the work platform 52b by means of cable 70 and hook 69.

When the scaffold is raised to a new position the guide members are extended out of their telescoped relation. When the scaffold is lowered the guide members are telescoped.

While I have illustrated and described certain preferred embodiments of my invention it will be understood that this invention may be otherwise embodied within the scope of the following claims.

I claim:

1. A portable scaffold particularly adapted for use in furnaces having an opening smaller than the interior diameter comprising a plurality of hollow elongated scaffold members telescoping within one another, cooperating lock means on the top and bottom of each said member adapted to hold the bottom of one member adjacent the top of the next smaller member in extensible position, support arms hinged at the top of the largest member adapted to be raised to the horizontal position and held there, removable grating means on said arms, yoke means on the said largest member adapted to receive a crane hook whereby said members may be raised in the furnace, a plurality of spaced guides made up of telescoping guide members, one of said guide members of each guide being attached to the largest scaffold member radially spaced from the center thereof and extending transversely from the plane of the top end thereof to form an adjustable length elevator shaft, cage means movable within said telescoping guide members and resiliently mounted guide wheels on said cage bearing on said telescoping guide members holding said cage centered therebetween.

2. A portable scaffold particularly adapted for use in furnaces having an opening smaller than the interior diameter of the furnace and including a charging floor spaced from the scaffold, said scaffold comprising a plurality of hollow elongated scaffold members telescoping within one another, cooperating lock means on the top and bottom of each said member adapted to hold the bottom of one member adjacent the top of the next smaller member in extensible position, support arms hinged at the top of the largest member adapted to be raised to the horizontal position and held there, removable grating means on said arms, yoke means on the said largest member adapted to receive a crane hook whereby said members may be raised in the furnace, a plurality of spaced guides made up of telescoping guide members, one of said guide members of each guide being attached to the largest scaffold member radially spaced from the center thereof and extending transversely from the plane of the top end thereof, the guide member remote from said one guide member being attached to the charging floor to form an adjustable length elevator shaft, telescoping screen members surrounding the guide members and corresponding in number thereto, the top and bottom screen members being fixed to the top and bottom guide members to telescope therewith, cage means movable within said telescoping guide members and resiliently mounted guide wheels on said cage bearing on said telescoping guide members holding said cage centered therebetween.

3. A portable scaffold particularly adapted for use in

furnaces having an opening smaller than the interior diameter of the furnace and including a charging floor spaced above the furnace, said scaffold comprising a plurality of hollow elongated scaffold members telescoping within one another, cooperating lock means on the top and bottom of each said member adapted to hold the bottom of one member adjacent the top of the next smaller member in extensible position, support arms hinged at the top of the largest member adapted to be raised to the horizontal position and held there, removable grating means on said arms, yoke means on the said largest member adapted to receive a crane hook whereby said members may be raised in the furnace, a plurality of spaced guides made up of telescoping guide members, the smaller diameter guide member of each guide being attached to the largest scaffold member radially spaced from the center thereof and extending transversely downwardly from the plane of the top end thereof and the largest guide member being removably attached to the charging floor to form an adjustable length elevator shaft, cage means movable within said telescoping guide members and resiliently mounted guide wheels on said cage bearing on said telescoping guide members holding said cage centered therebetween.

4. A portable scaffold particularly adapted for use in furnaces having an opening smaller than the interior diameter of the furnace and including a charging floor spaced above the furnace, said scaffold comprising a plurality of hollow elongated scaffold members telescoping

5

within one another, cooperating lock means on the top and bottom of each said member adapted to hold the bottom of one member adjacent the top of the next smaller member in extensible position, support arms hinged at the top of the largest member adapted to be raised to the horizontal position and held there, removable grating means on said arms, means on the said largest member adapted to receive a crane hook whereby said members may be raised in the furnace, a plurality of spaced guides made up of telescoping guide members, one of said guide members of each guide being attached to the largest scaffold member radially spaced from the center thereof and extending transversely downwardly from the plane of the top end thereof and the guide member remote from said one guide member being removably attached to the charging floor to form an adjustable length elevator shaft, cage means movable within said telescoping guide members and resiliently mounted guide wheels on said cage bearing on said telescoping guide members holding said cage centered therebetween.
